(57) **CLAIM**

The ornamental design for a doll eye assembly, as shown and described.

DESCRIPTION

FIG. 1 is an elevated, exploded-view illustration of the doll eye assembly; and

FIG. 2 is an elevated-view illustration of the doll eye assembly.

The broken line showing of the Doll Eye Assembly are for the purpose of illustrating portions of the article that form no part of the claimed design.

1 Claim, 1 Drawing Sheet
